Patented Sept. 21, 1971

221,941

COMBINED PIPE FLASHING AND SNOW DEFLECTOR UNIT OR SIMILAR ARTICLE

Herman G. Murphy, P.O. Box 446,
Incline Village, Nev. 89450

Filed Apr. 8, 1970, Ser. No. 22,311

Term of patent 14 years

Int. Cl. D23—01

U.S. Cl. D23—42

FIG. 1

FIG. 3

FIG. 4

FIG. 2

FIG. 5

FIG. 1 is a perspective view of a combined pipe flashing and snow deflector unit embodying my new design.

FIG. 2 is a side elevational view thereof.

FIG. 3 is a top plan view thereof.

FIG. 4 is a front elevational view thereof.

FIG. 5 is a bottom plan view thereof.

I claim:

The ornamental design for a combined pipe flashing and snow deflector unit or similar article, substantially as shown.
